(57) **CLAIM**

I claim the ornamental design for an elevated pet feeder having attachable extension bowls and containers, as shown and described.

DESCRIPTION

FIG. 1 is a perspective view of an elevated pet feeder having attachable extension bowls and containers, showing my new design.

FIG. 2 is a front elevational view, the opposite side being a mirror image thereof;

FIG. 3 is a left side elevational view thereof;

FIG. 4 is a right side elevational view thereof;

FIG. 5 is a top plan view; and,

FIG. 6 is a bottom plan view thereof.
